UNITED STATES PATENT OFFICE.

GEORGE L. CHASE, OF SEATTLE, WASHINGTON.

ENGINE.

1,328,033.

Specification of Letters Patent. Patented Jan. 13, 1920.

Application filed February 17, 1919. Serial No. 277,673.

To all whom it may concern:

Be it known that I, GEORGE L. CHASE, a citizen of the United States, residing at Seattle, in the county of King and State of Washington, have invented a certain new and useful Improvement in Engines, of which the following is a specification.

My invention relates to improvements in engines and the object of my invention is to provide a rotary engine of relatively simple construction that is free from vibration and extremely efficient as a power producer.

A further object of my invention is to provide an engine of a compact form of construction and one wherein the cylinders and the greater part of the engine structure rotate so that the momentum of the heavy rotating parts will contribute to produce an engine that will run very smoothly and will develop a great amount of power.

I accomplish these objects by devices illustrated in the accompanying drawings, wherein Figure 1 is a view in vertical mid section substantially on broken line 1, 1 of Fig. 2, of an engine constructed in accordance with my invention.

Fig. 2 is a view in sectional elevation of the same substantially on a broken line 2, 2 of Fig. 1.

Fig. 3 is a view partly in section and partly in elevation substantially on broken line 3, 3 of Fig. 1.

Fig. 4 is a view in elevation illustrating a detail of my invention.

Fig. 5 is a view in elevation showing a valve member embodied in my invention.

Fig. 6 is a fragmentary view partly in cross-section and partly in elevation illustrating the manner of securing the spokes 40 of the hub portion of the revolving frame, and,

Fig. 7 is a fragmentary view in cross-section illustrating the valve that controls the inlet and exhaust in an opposite position from that shown in Fig. 3.

Referring to the drawings, throughout which like reference numerals indicate like parts, the numerals 10 and 11 designate two triangular frame members that form a support for the engine. The upper portion of the frame member 10 is provided with a square aperture for the reception of a squared portion or block 12 on one end of which is formed an integral circular bearing shank 13, there being a shoulder 14 formed at the junction of the block 12 and shank 13

and the block 12 and shank 13 being provided with an interiorly disposed longitudinally extending passageway 15 that serves as a valve chamber and as a means for permitting inlet and exhaust of steam.

The shank 3 is provided with diametrically opposite passageways 16 and 17 that connect with grooves 18 and 20, respectively, in the periphery of the shank 13, the groove 18 extending almost one half way around the shank 13 and terminating just before it reaches the passageway 17 and the groove 20 extending almost half way around the shank 13 on the side opposite the groove 18 and terminating just before it reaches the passageway 16.

The block 12 projects outwardly through the frame member 10 and is provided near its outer end with an outlet opening 21 that is adapted to be connected with an exhaust pipe 22.

23 is a steam inlet pipe that is adapted to extend into the passageway 15 and is provided on its inner end with a valve member 24 that fits snugly within the passageway 15 and is provided on one side with a notch 25 adapted to register with an exhaust port and on the opposite side with a steam inlet orifice 26 adapted to register with a steam inlet port, the end of the valve member 24 is provided with a small projection 27 that is adapted to engage with the end wall of the passageway 15 and prevent the valve member from binding tightly the end wall of such passageway when it is rotated.

The steam inlet pipe 23 passes through a suitable stuffing box 28 at the point where it enters the passageway 15 and is provided exteriorly of the stuffing box with a fixed lever arm 30 by which the valve member 24 may be turned within the passageway 15 to reverse the direction of rotation of the engine as hereinafter explained.

Mounted for rotation upon the shank 13 is a square block or hub member 31 that terminates in a cylindrical shank 32 that is journaled for rotation within the upper portion of the frame member 11, the block 31 having radially disposed ports 33, 34, 35 and 36 arranged at diametrically opposite points such ports being adapted to register with the passageways 16 and 17 and with the grooves 18 and 20 in the course of their travel around the shank 13.

Fixedly secured to the block 31 and adapted to rotate therewith around the shank 13

is a relatively large circular frame having rear side wall 37, a peripheral portion 38 and a front spoke or supporting member 40, the circular frame corresponding to a wheel 5 with the block 31 as a hub. The circular frame may be balanced so that it will rotate smoothly by removing portions of the wall 37 after the wheel has been set up.

Extending inwardly in radial directions 10 from the peripheral portion 38 of the circular frame are four pairs of spaced lugs 41 within each pair of which is journaled a crank 42 upon the outer end of which is rigidly secured a gear wheel 43 that is adapted 15 to mesh with a fixed gear wheel 44 that is rigidly secured by screws 45 to the frame member 10. The fixed gear wheel 44 may also have a squared recess in its hub portion that is adapted to fit over the squared 20 block 12.

Rigidly secured to the four faces of the block or hub member 31 are four cylinders 45, 46, 47 and 48 within which are mounted reciprocable pistons 50 that are each connected 25 by rods 51 with cranks 52 on the crank shafts 42 in such a manner that when the pistons 50 are reciprocated the gear wheels 43 will be rotated.

The inlet and exhaust passageways 16 and 30 17 in the shank 13 are arranged so that when the piston in one of the cylinders, as shown in Fig. 3, is at the innermost point of its travel and the piston in the opposite cylinder is at its outermost point of its travel the 35 ports 35 and 33 will be closed, but as soon as the hub member is turned through a slight angle in a clockwise direction the port 33 will register with the passageway 16 and permit the steam to exhaust from the cylinder 45 while the port 35 will register with the passageway 17 and permit the inlet of steam into the cylinder 47, the exhaust and inlet both continuing through the grooves 18 and 20 respectively, until the hub 31 has 40 made substantially half of one complete revolution from the position shown in Fig. 3.

If the valve member 24 is rotated through one half of one complete revolution the port 16 will register with the steam inlet 45 passageway 26 and the port 17 will register with the exhaust groove 25 thus reversing the positions of the inlet and exhaust points which will have the effect of reversing the direction of rotation of the engine.

It will be seen from Figs. 3 and 7 that the grooves 18 and 20 terminate at a sufficient distance from the ports 17 and 20 respectively, so that there are two points where each of the ports 33, 34, 35 and 36 are completely closed both to exhaust and inlet during each revolution such points corresponding to the dead center positions of the piston and crank mechanism served by the respective ports.

Fig. 3 shows the piston of the cylinder

45 just ready to begin its exhaust stroke, the piston of the cylinder 46 about midway of its exhaust stroke, the piston of the cylinder 47 completing its exhaust stroke and just 70 ready to begin its power stroke and the piston of the cylinder 48 about midway of its power stroke and exerting a maximum turning effect.

Fig. 7 shows the cylinders in the same position but owing to the fact that the position of the valve 24 is reversed such cylinders would be moving contra-clockwise so that the cylinder 48 would be exhausting and cylinder 46 working.

As the pistons 50 reciprocate they will 80 rotate the wheels 43 which wheels will roll around on the fixed gear wheel 44 and carry the circular frame along with them, the force that tends to rotate the circular frame being applied through the pivot shafts 42. 85

From the above description it will be seen that substantially all of the heavier parts of the engine are carried by the circular frame and rotate therewith so that when they are properly balanced the entire engine 90 has the momentum to the weight of all of such parts and will run with a very smooth and steady motion.

When the engine is in motion it is apparent that centrifugal force will exert an 95 outward thrust on the pistons thereby working in conjunction with the steam on the power stroke of each piston.

The outer end of the shank 32 may be provided with a fixedly secured fly wheel 100 53 by means of which the power developed by the engine may be taken off.

In the engine herein illustrated the fixed gear wheel 44 is of the same pitch diameter, and is provided with the same number of 105 teeth as the gear wheels 43 so that the gear wheels 43 will travel one complete revolution around the fixed gear wheel 44 upon each complete reciprocation of the pistons 50.

It will be readily understood that if it is 110 desired to secure greater power and less speed in my engine the ratio between the gear wheels 44 and the gear wheels 43 may be varied, as for instance, the gear wheels 43 may be made one half the size of the 115 gear wheels 44 so that it will require two complete reciprocations of the pistons 50 and two complete revolutions of the gear wheels 43 to cause them to travel entirely around the circumference of the gear 120 wheels 44.

In a similar manner if the gear wheels 43 are made one quarter as large as the gear wheels 44 it will require four complete reciprocations of the pistons 50 to cause the 125 gear wheels 43 to travel once around the gear wheel 44. In case the ratio of the gear wheels 43 and the gear wheel 44 is made other than one to one the valve mechanism will necessarily be changed to permit 130

the intake and exhaust of steam at the proper intervals.

It will be readily understood that cylinders of different size may be incorporated 5 in an engine of this type and a suitable valve mechanism provided whereby the steam may exhaust from a smaller cylinder into a larger cylinder to thereby use steam expansively and secure a maximum efficiency 10 in a manner well known in the art of steam engines.

If it is desired the principles embodied 15 in the construction of my engine herein disclosed may be adapted to the construction 20 of an internal combustion engine, the driving effect of the several gear wheels being the same regardless of the nature of the agent used to reciprocate the pistons.

Obviously changes may be made in the 25 form, dimensions, and arrangement of parts 30 of my invention without departing from the spirit thereof.

What I claim is:

1. An engine comprising a supporting 25 frame, a hollow cylindrical shank having a squared portion on one end rigidly supported in said frame said shank having oppositely disposed ports extending through 30 the walls thereof, said ports each communicating with a groove on the periphery of said shank that extends around said shank to a point adjacent the opposite port, a valve member adapted to fit snugly within said hollow shank, an inlet pipe connected 35 with said valve member and having a passageway therethrough to connect with one of said ports in said shank said inlet pipe being smaller than the passageway in said hollow shank and said valve member afford-

ing an unobstructed outlet for exhaust, a 40 cylinder base mounted for rotation on said shank and having inlet and exhaust ports that register with the ports in said shank, radially disposed cylinders secured to said cylinder base, a circular frame secured to 45 said cylinder base and rotatable therewith, crank shafts journaled for rotation in said circular frame, a fixedly mounted gearwheel concentric with the axis of rotation of said circular frame, other gearwheels of 50 the same size as said fixedly mounted gearwheel secured to said crank shafts and meshing with said fixed gearwheel, pistons reciprocable within said cylinders, and rods connecting said pistons with said crank 55 shafts for rotating said gearwheels.

2. An engine comprising a fixed tubular shank having oppositely disposed ports extending through the walls thereof, said ports each communicating with a groove on 60 the periphery of said shank that extends around said shank to a point adjacent the opposite port, a valve member adapted to fit snugly within said hollow shank, an inlet pipe connected with said valve member and 65 having a passageway therethrough to one of said ports in said shank said inlet pipe being smaller than the passageway in said hollow shank and said valve affording an 70 unobstructed outlet for exhaust, and a cylinder base mounted for rotation on said shank and having ports that register with the ports and grooves in said shank.

In witness whereof, I hereunto subscribe my name this 11th day of February A. D. 75 1919.

GEORGE L. CHASE.
